JESSE D. LANGDON, OF LOS ANGELES, CALIFORNIA.

INTERNAL-COMBUSTION ENGINE.

Application filed August 4, 1923. Serial No. 127,101.

The present invention relates to internal combustion engines, and aims to provide an engine having novel and simple means for introducing air under pressure into the combustion chamber during the compression and exhaust strokes of the piston, in order to supercharge the combustion chamber with air and also scavenge the combustion chamber.

10 Another object of the invention is the provision of an engine having a novel piston and cylinder construction for obtaining, during the compression and exhaust strokes of the piston, the delivery of air under pressure into the combustion chamber for the intended purposes as above indicated.

15 A further object is the provision of a piston and cylinder construction of the kind indicated comprising a novel construction and arrangement of the component elements, to render the device practical and efficient.

20 With the foregoing and other objects in view, which will be apparent as the description proceeds, the invention resides in the construction and arrangement of parts, as hereinafter described and claimed; it being understood that changes can be made within the scope of what is claimed, without departing from the spirit of the invention.

25 30 The invention is illustrated in the accompanying drawing, wherein—

Figure 1 is a longitudinal section of the two cylinders, showing the piston in elevation in its upper or outer position.

35 Fig. 2 is a longitudinal section of the cylinders and piston, with the piston in lower or inner position.

Fig. 3 is a fragmentary plan view of the piston, cylinders and valves.

40 Fig. 4 is a sectional detail on the line 4—4 of Fig. 2.

45 As shown, the improvements are embodied in an internal combustion engine of conventional type, having the cylinder 7 and the cylinder head 8, and, in carrying out the invention, a second concentric cylinder 9 of smaller diameter and shorter length is disposed within the cylinder 7. The cylinder 9 has the outstanding portions 10 and 11 at the upper and lower ends of the cylinder 9, and fitted tightly within the cylinder 7. If the cylinder 9 is to be a unitary part with the cylinder 7, the portions 10 and 11 are integral with the cylinder 7, but the drawing depicts how an ordinary engine may be converted to embody the present improvements.

50 As shown, the portions 10 and 11 are connected by an outer cylindrical wall 12, and there is an annular air chamber 13 of constant volume in the bushing or member of which the cylinder 9 is a part. The lower or inner portion 11 has air ports 14 over which check valves 15 are seatable, and the upper or outer portion 10 has air ports 16 over which check valves 17 are seatable. 55 The valves are ball valves, as shown, and suitable guards or stops 18 are provided to prevent the valves from leaving their seats too far.

55 60 The usual piston which works in the cylinder 7 is substituted by a double-dia-metered piston having the section or part 19 of smaller diameter to work in the cylinder 9, and the section or part 21 of larger diameter to work in the cylinder 7 below the cylinder 9. The piston section 19 has packing rings 20 near its upper closed end, and the piston section 21 may also be provided with suitable packing rings. The piston section 21 has an upstanding boss 22 on 65 which the lower end portion of the piston section 19 is screw-threaded or otherwise secured, and the boss 22 has an opening 23 receiving the upper end of the usual connecting rod 24. The wrist pin 25 is inserted into a transverse opening in the boss 22 and through the bearing of the connecting rod 24, before the piston sections 19 and 21 are assembled, so that when the piston section 19 is screw-threaded over the boss 22, it will 70 retain the wrist pin 25 in place, as seen in Fig. 4.

75 80 An air compression chamber 26 is provided around the piston section 19 between the portion 11 and piston section 21, and the piston section 19 is provided near its upper end with ports 27 to be moved below the portion 11 when the piston is in its lowermost position, as seen in Fig. 2.

85 90 95 The engine is of the usual four cycle operation, and has the usual intake and exhaust valves 28 as shown in Fig. 3, which are actuated the same as usual. The only change necessary in the engine is the insertion or use of the cylinder 9 within the cylinder 7 and the use of the double-dia-metered piston. A richer fuel mixture is provided, and the timing of the ignition being advanced will also increase the efficiency.

100 105 110 In operation, during the intake stroke of the piston, the downward movement of the piston section 19 in the cylinder 9 will draw

the carbureted air or fuel mixture into the combustion chamber in the usual manner, and the piston section 21 moving downwardly will enlarge the air compression chamber 26, so that when the ports or openings 27 move below the portion 11, air from within the crank casing will flow through the opening 23 of the piston section 21 and through the openings or ports 27 into the chamber 26. Then, when the piston moves through its compression stroke, the piston section 19 moving upwardly in the cylinder 9 will compress the fuel mixture within the combustion chamber, and, at the same time, the air in the chamber 26 is compressed and forced upwardly through the ports 14 into the air chamber 13, from which the compressed air is forced upwardly through the ports 16 into the combustion chamber. This delivers a supply of air under pressure into the combustion chamber during the compression of the fuel mixture, and the mixture of carbureted air and fresh air is thus compressed within the combustion chamber, which is preferably of the same size as customary with the piston in its uppermost position, as seen in Fig. 1. The mixture is then ignited, thereby forcing the piston section 19 downwardly, and the downward movement of the piston section 21 will result in the chamber 26 again being filled with air, so that during the exhaust stroke the air in the chamber 26 is forced into and through the chamber 13. This will discharge air through the ports 16 into the combustion chamber during the exhaust stroke of the piston, so as to drive out the burnt gas from the combustion chamber, and thereby scavenge the engine, and leaving only fresh air in the combustion chamber when the intake stroke is started.

It will be noted that although the stroke of the piston may be the same in length as that of the ordinary piston (not shown) used in the cylinder 7, the cylinder 9 is of smaller diameter (one half of that of the cylinder 7 as shown) so that in proportion to the diameter of the cylinder 9 with reference to the cylinder 7 a longer stroke is employed, for high speed operation. The engine is thus converted into a small bore, long stroke engine. With the piston in lowermost position, as seen in Fig. 2, the capacity of the chamber within the cylinder 9 plus the capacity of the chamber 26 equal the capacity within the cylinder 7 when using the ordinary piston, so that the same amount of mixture is compressed into the combustion chamber during the compression stroke, and during the explosion stroke the expanding burning gas is effective on a much less area of the piston than when using the ordinary piston for the cylinder 7.

With the present improvements, the engine

will operate at high speed with increased efficiency, and the improvements may be embodied in existing engines as well as being incorporated in new engines when built.

The air flowing through the piston from the crank casing will assist in cooling the engine. Furthermore, the heat from the combustion or explosion chamber within the cylinder head 8 and cylinder 9 is transmitted through the wall of the cylinder 9 so as to heat the air in the chamber 13. This assists in cooling the engine, and, furthermore, the air in the chamber 13 is expanded, in order to use the heat of the engine to advantage. Thus, the air within the chamber 13 being highly heated will increase considerably in volume, due to expansion, thereby discharging the heated air through the ports 16 into the combustion chamber. This heated air mixes with the inflowing mixture, so as to assist in vaporizing the fuel and rendering the mixture more highly combustible. During the explosion stroke of the piston, the air within the chamber 13 being heated will, after the expansion of the burning gas is spent, cause the expansion of the air from the chamber 13 into the combustion chamber to assist in driving the piston downwardly. The engine therefore embodies therewith a thermal principle of operation, and the admission of air serves several purposes, namely, (1) to supercharge the engine, (2) to scavenge the engine during the exhaust stroke of the piston, (3) to cool the engine, (4) to heat and vaporize the inflowing fuel, and (5) to add power by utilizing the heat generated by the combustion of the fuel.

Having thus described the invention, what is claimed as new is:

1. A four cycle engine comprising two concentric cylinders of different diameters, a piston having sections of different diameters working in said cylinders, with an explosion chamber within the cylinder of smaller diameter and an air compression chamber within the cylinder of larger diameter and means for admitting air to the air compression chamber, usual intake and exhaust valves for said explosion chamber for four cycle operation, an individual air chamber of constant volume for said cylinders only communicating with the explosion and compression chambers and stationary relatively to said cylinders for the flow of air by compression through said thirdnamed chamber into the explosion chamber from the air compression chamber, and valve means preventing the flow from the explosion chamber to the thirdnamed chamber and from said thirdnamed chamber to the compression chamber.

2. A four cycle engine comprising two concentric cylinders of different diameters, a piston having sections of different diam-

eters working in said cylinders, with an explosion chamber within the cylinder of smaller diameter and an air compression chamber within the cylinder of larger diameter and means for admitting air to the air compression chamber, usual intake and exhaust valves for said explosion chamber for four cycle operation, an individual air chamber of constant volume for said cylinders only having an inlet communicating with said compression chamber and an outlet communicating with said explosion chamber for the flow of air by compression through said thirdnamed chamber into the explosion chamber from the air compression chamber, and check valves for said inlet and outlet to prevent the flow from the explosion chamber to the thirdnamed chamber and from said thirdnamed chamber to the compression chamber.

3. A four cycle engine comprising two concentric cylinders of different diameters, a piston having sections of different diameters working in said cylinders, with an explosion chamber within the cylinder of smaller diameter and an air compression chamber within the cylinder of larger diameter and means for admitting air to the air compression chamber, usual intake and exhaust valves for said explosion chamber for four cycle operation, an annular chamber surrounding the cylinder of smaller diameter and communicating with the explosion and compression chambers for the flow of air by compression through said thirdnamed chamber into the explosion chamber from the air compression chamber, and valve means preventing the flow from the explosion chambers to the thirdnamed chamber and from said thirdnamed chamber to the compression chamber.

4. A four cycle engine comprising two concentric cylinders of different diameters, a piston having sections of different diameters working in said cylinders, with an explosion chamber within the cylinder of smaller diameter and an air compression chamber within the cylinder of larger diameter and means for admitting air to the air compression chamber, usual intake and exhaust valves for said explosion chamber for four cycle operation, an annular chamber surrounding the cylinder of smaller diameter and having an inlet communicating with the compression chamber and an outlet communicating with the explosion chamber for the flow of air by compression through said

thirdnamed chamber into the explosion chamber from the air compression chamber, and check valves for said inlet and outlet to prevent the flow from the explosion chamber to the thirdnamed chamber and from the thirdnamed chamber to the compression chamber.

5. A four cycle engine comprising a cylinder, a bushing fitted therein and forming a cylinder of smaller diameter, a piston having sections of different diameters working in said cylinders, with an explosion chamber within the secondnamed cylinder and an air compression chamber within the firstnamed cylinder and means for admitting air to the air compression chamber, said bushing having a chamber therein communicating with both the explosion and compression chambers, and valve means preventing the flow from the explosion chamber to the thirdnamed chamber and from said thirdnamed chamber to the compression chamber.

6. A four cycle engine comprising a cylinder, a bushing fitted therein and providing a cylinder of smaller diameter, a piston having sections of different diameters working in said cylinders, with an explosion chamber within the secondnamed cylinder and an air compression chamber within the firstnamed cylinder and means for admitting air to said air compression chamber, said bushing having an annular chamber therein surrounding the secondnamed cylinder with an inlet communicating with said compression chamber and an outlet communicating with said explosion chamber, and check valves for said inlet and outlet to prevent the flow from the explosion chamber to the thirdnamed chamber and from said thirdnamed chamber to the compression chamber.

7. An engine comprising a cylinder, a bushing fitted within said cylinder and forming a cylinder of smaller diameter, a piston having sections of different diameters working in said cylinders, with an explosion chamber within the secondnamed cylinder and an air compression chamber within the firstnamed cylinder and means for admitting air to said compression chamber, said bushing having a chamber establishing communication between said compression and explosion chambers and valve means preventing the flow from the explosion chamber to the compression chamber.

In testimony whereof I hereunto affix my signature.
